UNITED STATES PATENT OFFICE.

CHARLES L. EMMONS, OF GARWOOD, NEW JERSEY.

DESIGN FOR A CASING FOR PLAYERS FOR PIANOS.

SPECIFICATION forming part of Design No. 36,565, dated September 22, 1903.

Application filed July 25, 1903. Serial No. 167,048. Term of patent 7 years.

To all whom it may concern:

Be it known that I, CHARLES L. EMMONS, a citizen of the United States, residing at Garwood, New Jersey, (post-office address Garwood, New Jersey,) have invented a new, original, and ornamental Design for a Casing for Players for Pianos, of which the following is a specification, reference being had to the accompanying drawings, forming part hereof.

10 Figure 1 is a front view, and Fig. 2 a side view, of the casing.

What I claim as new, and desire to secure by Letters Patent, is—

The ornamental design for the casing for players for pianos, as shown.

In testimony whereof I have signed this specification in the presence of two subscribing witnesses.

CHARLES L. EMMONS.
